UNITED STATES PATENT OFFICE.

HORACE B. CHAFFEE, OF BROOKLYN, NEW YORK.

WINDOW.

1,363,837.

Specification of Letters Patent. Patented Dec. 28, 1920.

Application filed April 29, 1919. Serial No. 293,492.

To all whom it may concern:

Be it known that I, HORACE B. CHAFFEE, a citizen of the United States, residing at Brooklyn, county of Kings, and State of New York, have invented certain new and useful Improvements in Windows, of which the following is a specification.

This invention relates to windows, and is particularly directed to improved window construction whereby the sashes, as well as the frame of a window screen, may be easily and expeditiously assembled within a window frame.

The object of the invention is to provide a sheet metal construction which will mount the sashes and the screen frame for free sliding movement without binding, and to so form the parts that the structure may be readily painted from time to time, as occasion requires, without necessitating the exercise of care against painting the parts so as to preclude easy sliding movement thereof. The construction is such that the structural elements may be painted in the usual manner without any danger of filling the joints, and after being so painted the window sash may be readily slid up and down without showing marks on the paint due to the sliding action between the sashes and the guides in which they travel.

A further object of the invention is to provide a construction of this character which will obviate the necessity of weather-stripping, the parts being so formed that wind or rain cannot possibly beat through the joints.

Another object of the invention is to provide improved means for mounting the screen in a position for sliding movement, and maintaining the said screen in co-operative relation to the adjacent window sash through the agency of the means which maintains the window sash in place.

Features of the invention other than those specified will be apparent from the hereinafter detailed description taken in conjunction with the accompanying drawings.

In the accompanying drawings I have illustrated one practical embodiment of the invention, but the construction therein shown is to be understood as illustrative only, and not as defining the limits of the invention.

Figure 1 is a perspective view of a window

construction embodying the present invention;

Fig. 2 is a detail of the improved screen guide which I preferably employ; and

Fig. 3 is a horizontal section through a part of the construction of Fig. 1.

Referring to the drawings, 1 indicates the pulley-stile of a window frame, which, in accordance with the present invention, forms the front wall of the sash-weight slides or pockets, but the exposed face of said stile, instead of being cut away, or rabbeted, for the blind and parting strips, as is usual, is made perfectly flat as shown. The usual false jamb may be associated with the inner edge of the pulley-stile 1 if desired, but this forms no part of the present invention. Furthermore, the window stop, which normally serves to hold the inner sash against the parting strip, is dispensed with, as both sashes, in accordance with this invention, are mounted for vertical sliding movement in sheet metal guides 2 and 3, next to be described.

The guides 2 and 3 for both the inner and outer sashes 4 and 5, respectively, are identical with one another, and are bent up from sheet metal in the form of a channel section, the base of which is secured to the stile 1 by screws 6 and 7, respectively. The guides 2 and 3 are mounted in vertical position on the exposed face of each pulley-stile 1 of the window frame and extend from the sill up to the head-stile which forms the top of the frame, the two guides being placed side by side and in engagement with one another.

The free edges of each channel section are provided with box shaped flanges 8 and 9, one side of each of which is provided with an inwardly projecting vertical rib. The side 10 of each flange 8 has a rib 17 and a similar rib 17 is formed on the side 11 of each flange 9. Into the box shaped flanges 8 and 9 are adapted to interfit box-flanges 12 and 13 of corresponding shapes which are formed on plates 14 and 15 adapted to be screwed on to the window sashes 4 and 5, and held in place by screws 16.

The vertically extending ribs 17 are adapted to engage the box-flanges 12 and 13 of the plates 14 and 15 in substantially line contacts. All of the flanges are so proportioned that the sides 10 and 11 of the flanges 8 and 9 of the guides 2 and 3 will be free from engagement with the plates 14 and 15.

except at the ribs 17, so as not to cause friction between the flanges 8 and 9 and said flanges 12 and 13 when the window sashes are raised or lowered. During this operation the box-flanges 12 and 13, which are carried by the window sashes, will engage with the flanges only in the line contacts furnished by the ribs 17, and, operating in this manner, the sashes may be readily raised 10 or lowered with a minimum of friction.

By maintaining the various flanges of the fixed and stationary parts in spaced relation as described, and providing only line contacts between the fixed and moving parts, 15 friction is not only obviated, but, it is impossible to paint the parts so that they will become stuck together when the paint dries. This is manifest when it is noted that the ribs 17 are positioned at the innermost parts 20 of the interfitting flanges where it is practically impossible to introduce paint except before assembling the parts. The parts may be properly painted before assembling, but, when once assembled, the sticking of the 25 sash due to want of care during the painting thereof is absolutely avoided.

In the drawings, I have illustrated a practical manner in which a window screen may be readily supported in substantially the 30 same manner as described with reference to the sashes. The guide 18, for supporting the screen, is in the form of a plate 19 flanged after the same manner as the guides 2 and 3, and provided with a rib 17' corresponding 35 to the rib 17. The plate 19 is adapted to be slipped in between the inside sash guide 2, and the pulley-stile 1, as shown in Figs. 1 and 3 and is provided with slots 20 which so cut out the plate 19 as to clear the screws 40 6. By tightening up the screws 6 to hold the guide 2 in position, the plate 19 is simultaneously clamped between the guide 2 and the pulley-stile. The frame 21, which carries the window screen, is provided with a 45 plate 14' which is shown of a construction identical with the plate 14 of the sashes, and the box-flange of this plate is adapted to interfit with the flange of the plate 19, and mount the screen frame 21 for vertical 50 sliding movement. The plate 14' is secured to the frame 21 by means of screws 22. It will be understood that the thickness of the screen frame 21 may be readily compensated for by sliding the plate 19 back of the guide 55 2 and locking the plate 19 by tightening the screws 6 in such position that the screen may be readily raised or lowered without rubbing the adjacent plate 14 of the inner sash.

In the accompanying drawings the invention 60 is specifically shown, and has hereinbefore been described as particularly adapted for mounting sashes and screens for sliding movement in a window frame, but I wish it understood that the invention may be used 65 for sliding doors. In any of its embodi-

ments it will adequately preclude the sticking of the movable element relative to the fixed element as a result of painting the parts. The invention is not only adapted to be incorporated in buildings of the ordinary 70 character but it is also adapted for employment in portable buildings due to the ease and economy with which it may be installed. Not only is the invention to preclude the sticking of the sashes but, because of the 75 interlocking flanges, it constitutes an efficient form of weather stripping so that the employment of extraneous means to preclude the entrance of rain or wind into the building is rendered unnecessary where the construction illustrated is employed.

In the preferred embodiment of the invention the guides 2 and 3 are preferably made U-shaped as shown and are flanged as described to provide run-ways over the co-operating flanges of the window sashes. The adjacent faces of the guides 2 and 3 are placed in face abutting relation as shown and partake of substantially the same position as the parting strip in wooden window 90 construction. However, the parts may be greatly simplified by dispensing with those portions of the guides 2 and 3 which lie between the dotted lines X and Y in Fig. 1. This will of course dispense with the lateral 95 portions of said guides which carry the adjacent flanges 8 and 9 as well as the adjacent plates 14 and 15 which are mounted on the sashes and in lieu of these dispensed with portions an ordinary form of parting 100 strip is employed against the opposite edges of which the free edges of the guides 2 and 3 are adapted to abut. This modified construction is manifestly much simpler than the form of the invention shown in Figs. 1 105 and 3 and of course more economical. The preferred construction is, however, superior since the sashes are shiftable along line contacts which allow of much freer movement of a window and less liability to sticking 110 than the construction wherein the sashes directly engage with the faces of the parting strip.

Having thus fully described the invention, what I claim as new, and desire to secure 115 by Letters Patent is:

1. Means for mounting a movable element for slidable movement relative to a fixed element, embodying a channeled guide mounted on the fixed element and provided at its free edges with inwardly extending box-shaped flanges, and shaped flanges mounted on the movable element and housed in interfitting relation within the flanges of the guide, one 120 of each set of the coacting flanges being provided with a rib adapted to maintain the interfitting flanges in spaced relation and having line contact between them.

2. Means for mounting a plurality of movable elements for slidable movement rel- 130

- ative to a fixed element, embodying a guide provided with a box-shaped flange, a movable element having a box-shaped flange interfitting with the flange of the guide, a second guide provided with a box-shaped flange, a second movable element having a box-shaped flange interfitting with the flange of the second guide, and means for simultaneously mounting both of the guides 5 on the fixed element to be capable of allowing relative adjustment between the guides to compensate for movable members of different thickness.
3. Improved window construction embodying a window frame provided at each side thereof with a pair of vertical parallel box-shaped flanges, and a sash mounted in the frame, each stile of which is provided on both its inner and outer faces with plates 10 having box-shaped flanges interfitting with the box-shaped flanges of the frame, one of each pair of the coacting box-shaped flanges of the sash and frame being provided with a longitudinal rib, whereby the coacting box-shaped flanges engage one another in line contact.
4. Improved window construction embodying a window frame, each side of which is provided with a pair of upright parallel 15 box-shaped flanges, a sash mounted within the frame, and a box-shaped sheet metal flange secured on one face of each stile of the sash and interfitting with the box-shaped flanges of the frame.
5. Improved window construction embodying a window frame provided at each side with an upright sheet metal channel section, each channel section being provided at its edges with a box-shaped flange, and 20 a sash mounted within the frame and each stile of which is provided with a flange interfitting with each of the box-shaped flanges of the channel section at the corresponding side of the frame.
6. Improved window construction embodying a window frame provided at each side thereof with an upright channel section, having a box-shaped flange at each edge thereof and which box-shaped flange is 25 formed with an interior vertical rib, a window sash mounted within the frame and ad-
- jacant each face of which is formed a flange interfitting with the box-shaped flange of the channel section and engaging with the rib of said box-shaped flange to provide a line contact between the flange of the sash and the flange of the channel section. 55
7. Improved window construction embodying a window frame provided on each side thereof with a plate, one edge of which is provided with a box-shaped flange and the body of which plate is provided with transverse slots, a movable frame provided with a flange interfitting with the box-shaped flange of said plate, a channel section positioned in upstanding relation at either side of the frame and overlying a portion of said plate, each edge of the channel section being provided with a box-shaped flange, a sash frame, each stile of 60 which is provided with a box-shaped flange interfitting with the flanges of the channel section, and securing means passing through the base of the channel section and through the slots of the plate into the window frame 65 for simultaneously mounting both the channel section and plate in position on the window frame but permitting of adjustment between the channel section and said plate to compensate for the thickness of the movable frame. 70
8. Improved window construction embodying a window frame, an upright channel section positioned at either side of the frame, a sash mounted for sliding movement between said channel sections, and screws passing through the base of the channel sections into the frame, in combination with a plate positioned between the base of each channel section and the frame and 75 slotted to permit of lateral adjustment of the plate, said plate being provided at one of its vertical edges with a box-shaped flange, and a screen frame provided at each of its vertical edges with a flange interfitting with the flange of the plate, whereby the plate may be adjusted to assure proper 80 sliding relation between the sash and the screen frame. 85

In testimony whereof, I have signed my name to this specification.

HORACE B. CHAFFEE.
